CLAIM

The ornamental design for an auxiliary golf club holder, as shown and described.

DESCRIPTION

FIG. 1 is a perspective view of an auxiliary golf club holder in accord with our new design;

FIG. 2 is an elevational view of our new design as taken from the left of FIG. 1;

FIG. 3 is top plan view of the auxiliary golf club holder; and,

FIG. 4 is a partial prospective view of the lower end of the auxiliary golf club holder.
